UNITED STATES PATENT OFFICE

HENDRIK JAN JAKOB JANSSEN, OF ROTTERDAM, NETHERLANDS, AND HEINRICH BORSARI, OF ZOLLIKON-ZURICH, SWITZERLAND, ASSIGNORS TO THE FIRM OF BORSARI & CO., OF ZOLLIKON-ZURICH, SWITZERLAND.

RECEPTACLE.

1,189,694.

Specification of Letters Patent.

Patented July 4, 1916.

Application filed April 16, 1914. Serial No. 832,215.

To all whom it may concern:

Be it known that we, HENDRIK JAN JAKOB JANSSEN, a subject of the Queen of the Netherlands, residing at Rotterdam, Netherlands, 5 and HEINRICH BORSARI, a citizen of the Republic of Switzerland, residing at Zollikon-Zurich, Switzerland, have invented certain new and useful Improvements in Receptacles; and we do hereby declare the following 10 to be a full, clear, and exact description of the invention, such as will enable others skilled in the art to which it appertains to make and use the same, reference being had to the accompanying drawings, and to letters or figures of reference marked thereon, 15 which form a part of this specification.

The hitherto known barrels for storing beer and other liquids have usually been made of wood. It has, however, heretofore 20 been proposed to make such barrels of metal, for instance, iron, steel, aluminium or the like. But, without counting that the cost of production of such barrels is very high, it has been found that metal barrels, and particularly when they are of a large size, cannot be manufactured in an advantageous manner, it being very difficult to join together the different parts of the barrel in a 25 tight manner. Further, there have to be met considerable difficulties when the barrel has to be fitted up at the place of erection, for instance, in a cellar. The connection of the different parts of the barrel by means of screws or the like has also the drawback, 30 that the cleaning of the inner parts is rendered more difficult, and that these connection members may cause infection. Also the manufacture of steel-barrels built up of single iron-plates welded together in an autogenous manner and lined on the inside with a 35 layer of pitch is not advantageous, since too much time and room have to be wasted. Owing to these drawbacks of metal-barrels more attention has again been paid in recent 40 years to the concrete and in particular to the ferro-concrete. Barrels made of ferro-concrete can be manufactured in any size even in cellars; such barrels moreover do not rust and they involve only small expense. The 45 construction of reservoirs for fluids to be made of ferro-concrete and provided on the inside with a lining of pitch or thin metal walls renders it necessary to use a great number of wood laggings and scaffolds and the

walls of such reservoirs have to be made very 55 thick partly in consideration of the process of manufacturing and partly to provide sufficient room for placing the iron armoring. Further, the manufacturing of the barrel and the hardening and drying of the material used, involve a great waste of time and if the barrel is subjected to an internal pressure, as it is usually the case, there has to be used for the armoring of such barrels of concrete a large quantity of iron. Finally, 60 the inner pressure causes a slight outward deflection of the walls, which can hardly be prevented, so that cracks and leaks are produced. If, for the purpose of eliminating these disadvantages, there would be chosen 65 a round cross-section for the reservoir in which the liquid has to be stored, difficulties in the manufacturing of such a reservoir would arise, the stamping being rendered 70 more difficult and expensive laggings and scaffolds having to be provided for. Moreover such a construction has the drawback that any pressure arising inside the reservoir sets off tensile stresses favoring the formation of cracks and producing leaks in the 75 interior layers of the reservoir made of concrete.

The object of this invention is to eliminate the drawbacks to be found in connection with reservoirs made of ferro-concrete. 80

The main feature of the invention consists in the use of molding pieces having a shape corresponding to that of the walls and bottoms of the reservoir, said pieces forming the reservoir when they are joined together. Around the so formed reservoir there is put an armoring, holding together the single pieces of the reservoir while it is built up. The armoring may also act as a tensioning device, so that it presses together 90 said molding pieces. There might, however, also be used tensioning devices arranged independently from the armoring.

Several barrels made according to the process forming the subject matter of this 100 invention are shown by way of example in the accompanying drawings, in which:

Figure 1 shows a front elevation of a first form of a barrel, the round irons embedded in the molding pieces being not 105 shown for the sake of clearness. Fig. 2 shows a plan view of Fig. 1, the tensioning means being shown in dotted lines to sim-

plify the drawing. Fig. 3 shows a cross-section of one end of this barrel. Figs. 4, 5, 6 and 7 show details of the barrel, Fig. 6 being a section on the line 6—6 of Fig. 5. Fig. 8 shows a detail of a second form of a barrel made according to this invention and Fig. 9 shows a section through a third form of such a barrel.

The walls of the reservoir shown in Figs. 10 1—7 consist of molding pieces *a*; as such molding pieces there can be used, for instance, concrete plates provided with an inner lining. The armoring surrounding the barrel consists of a netting made of 15 single wires *r* having a round cross section and embedded in the longitudinal and transverse directions of the concrete plates *b*. These plates *b* pressed closely to the plates *a* are smaller than the latter, in order to 20 provide grooves *R* in which the wires *r* may be hooked together to form the continuous netting surrounding the whole reservoir. Into the grooves *R* there are further put additional tensioning straining members 25 arranged independently from said netting. These tensioning members put around the outer surface of the reservoir or barrel consist preferably of flat-irons *f*, while the tensioning members put around the bottoms 30 of the reservoir or barrel consist of chains *k*. The tensioning members have tensioning screws *s* provided with a right hand side and left hand side thread, said screws permitting adjustment of the tension. After the 35 erection of the barrel the grooves *R* are filled out with cement and the surface of the barrel is then polished, so that all iron-parts are prevented from rusting and a smooth outer barrel surface is obtained. 40 The insulating substance on the inside of the barrels is flushed at the joints of the molding pieces *a* and polished, so that also the inside of the barrel forms an entirely smooth surface. If the molding pieces are 45 made of another material, for instance glass, the joints are jointed with a suitable cement.

Fig. 7 shows on an enlarged scale a flat-iron *f* provided with a tensioning screw *s* having a left hand side and a right hand side thread and further provided with a chain *k* connected near said screw *s* to the flat-iron *f*.

Fig. 8 shows a single ring of a barrel surrounded by a strongly strained wire winding *r*, acting as a straining armoring. This wire winding of iron connects the single elements of the ring in a sure manner and makes the provision of a netting unnecessary. The wire wound around the ring having been elongated to a certain extent, owing to the strain to which it has been subjected during the winding operation exerts upon the segments and their joints a great resilient pressure. If the wire has been wound in an equal manner

around said ring no varying pressures will be found in said ring. Such a wire armoring makes the provision of any connections between the different segments of the ring entirely unnecessary. In this instance, however, the material of which the segments of the ring are made, must be practically non compressible.

Fig. 9 shows a barrel having approximately a cylindrical shape, the lower molding pieces of this barrel serving as a support. This shape of the cross-section permits a greater saving of room.

The device according to this invention results in the following advantages: First, no 80 expensive wood laggings and scaffolds of any sort have to be provided, only a few centers being necessary; second, the time necessary for the erection of the barrel in the cellar is reduced to a minimum; third, 85 the thickness of the wall may be reduced to a minimum and still obtain stability; fourth, the molding pieces may be provided with the necessary insulating mass while they are manufactured and they may also 90 be made of other materials than concrete, for instance, clay, glass and the like may be used, and fifth, the formation of cracks and leaks is prevented, the inner walls being subjected by the straining device to a 95 pressure.

What we claim is:

1. A receptacle, particularly adapted to be subjected to an inner pressure, comprising preformed plates forming the ends and side 100 walls, a frame consisting of metallic reinforcing pieces enveloping said plates, a second frame consisting of reinforcing bars provided with adjustable tension members and resting on said first mentioned frame, 105 the plates being bound together by the two frames to form a unitary structure, and a layer of cement laid on said plates and embedding said frames.

2. A receptacle, particularly adapted to be subjected to an inner pressure, comprising preformed plates forming the ends and side walls, a plurality of smaller preformed plates placed on said first mentioned plates, 110 crossed reinforcing wires embedded in the 115 smaller plates and projecting beyond the edges of the latter, the spaces between the smaller plates forming recesses in which the projecting ends of the wires are connected, reinforcing bars under tension in said recesses, and means for adjusting the tensional strain of said bars whereby the plates forming the ends and side walls are bound together to form a unitary structure and a 120 filler of cement in the recesses.

3. A receptacle, particularly adapted to be subjected to an inner pressure, comprising preformed plates forming the ends and side walls, a plurality of smaller preformed plates placed on said first mentioned plates, 125 130

crossed reinforcing wires embedded in the smaller plates and projecting beyond the edges of the latter, the spaces between said smaller plates forming recesses in which the 5 projecting ends of the wires are connected, flat-irons arranged in recesses parallel to the longitudinal axis of the receptacle acting as reinforcing and tensional straining members and resting on the reinforcing wires, chain-links connecting the flat-irons, screws provided with left hand and right hand threads, each connecting a flat-iron to a chain-link to 10 permit adjustment of the tensional strain, the plates forming the ends and side walls 15 being bound together by said frame to form a unitary structure, and a filler of cement in said recesses.

4. A receptacle, particularly adapted to be subjected to an inner pressure comprising 10 adjacent rings consisting of preformed plates of a non-compressible material and forming the side walls, preformed plates also of a non-compressible material forming the ends of the receptacle, wire wound around

said rings and subjected to a tensional strain 25 corresponding to the inner pressure of the receptacle, reinforcing bars under tension resting on said wire and crossing it at right angles, said bars being provided with means for adjusting the tensional strain, the plates 30 forming the rings and the ends of the receptacle being bound together by said wire and reinforcing bars to form a unitary structure, and a layer of cement on said plates and embedding the wire and reinforcing 35 bars.

In testimony that we claim the foregoing as our invention, we have signed our names in presence of two subscribing witnesses.
